UNITED STATES PATENT OFFICE.

FRANCISCO FERNÁNDEZ ASENJO Y PEREZ DEL RIO, OF MADRID, SPAIN.

RAIL.

Application filed July 23, 1926, Serial No. 124,487, and in Spain September 3, 1925.

It is customary in laying rails, to provide a space between the oppositely disposed end faces of the lengths of the rails in line, sufficient to permit of the free longitudinal expansion of the respective connected lengths of the rails due to increase of temperature, and thus to avoid deformation of the rails and consequent derailment of the rolling stock.

10 In practice, the spaces thus left between the ends of the lengths of the rails permit of the flexure of the ends of the rails in the passage over them of the rolling stock, by reason of the weight of the latter, whereby 15 as the wheels leave the end of one rail, the adjacent end of the other rail in line is disposed at a slightly higher level, whereby undesirable shocks are imparted to the rolling stock, which result in inconvenience to passengers and disadvantages in the maintenance of the rolling stock and the permanent way.

It is one of the objects of the invention to avoid these disadvantages by means that are 25 equally applicable to railway rails and tramway rails.

According to the invention, an intermediate member is applied between adjacent lengths of rail in line, and serves to connect 30 them, and this intermediate member is provided with a part of a shape corresponding to the head of the rails to extend over the space between the ends of the rails in line, so that thus, on a wheel passing from the end 35 of one rail, it becomes supported on the intermediate member, and on leaving the intermediate member, it then passes to and is supported by the adjacent rail.

The said intermediate member is mounted 40 and connected in such manner that the flexure of the adjacent rail ends cannot take place independently, and thus the adjacent rail ends under load are not momentarily disposed at different levels, and thus resulting shocks are avoided. Moreover, the movement of the wheels from rail to rail and over 45 the jointing member, is smooth and does not cause vibration.

The invention is illustrated by way of example, in the accompanying drawing applied to a connection between two adjacent lengths of a railway rail in line.

Figure 1 is a perspective view of the intermediate member ready to be mounted between two lengths of rails in line, provided as illustrated in perspective view in Figure 2.

Figure 3 is a plan view showing the completed connection of the ends of two adjacent rails in line and showing the intermediate member disposed upon and between the opposite ends of the lengths of rail, while

Figure 4 is a side view opposite to that at which the intermediate member is applied.

As illustrated in the accompanying drawing, the rails 1 and 2 disposed in line, have their heads partially removed to form recessed parts 3 and 4 by which two inclined faces are thus formed extending from the inner side of the rail heads downwardly to the outer side, and by which also adjacent end faces are formed which are inclined outwardly from the inner side of the rail heads to the outer side thereof, whereby the angle indicated at 5 in Figure 3 between the inclined end faces is obtuse.

The intermediate member, Figure 1, is provided with a part 7 which is complementary to the recesses formed in the heads of the adjacent lengths of rail that is to say the intermediate member is provided with an inclined bottom face which is adapted to lie upon the inclined faces of the recessed parts 3 and 4 and with inclined end faces that are adapted to lie in contact with the end faces of the said recessed parts, so that when the intermediate members is applied in position, it completely fills the recesses, and its upper surface 8 forms a continuation to the upper part of the normal section of the head of the 80 connected rails, so that thus, on the intermediate member being set into position, the part 7 forms, with the adjacent rail heads of normal section at 9 and 10, a substantially 85 continuous rail head and surface upon which the wheels of the rolling stock may roll, and in which, instead of the usual butt jointing space 6 being exposed on the top of the rail head, a joint 11, 12, 13 and 14 is formed that extends from one side of the rail to the 90 other, in the manner indicated in Figure 3.

The intermediate member, Figure 1, in addition to the part 7 integrally formed with it, is provided with a lower mounting plate 15 having holes 16, 17, 18, 19 therein, 105 by which it is adapted to be fixed by means of bolts 20, 21, 22, 23 to the web of the rail in position beneath the normal head thereof. This mounting plate, at its lower edge, is applied against the feet 34, 35 of the respective adjacent rail lengths, in such manner 110 that the ends of the lengths are not free in

their movements of flexure. If it be supposed that the rolling stock passes from left to right by reference to Figure 3, the wheel which is supported upon the whole width 24 of the rail head, by reason of the acute angle 25 and its opposite angle 26, gradually loses the support of the rail 1 and gradually acquires support upon the part 7 of the intermediate member until the line 27 is attained, whence it gradually loses support from the part 7 of the intermediate member and gradually acquires support upon the rail 2 by reason of the acute angle formed at 28 and the opposite acute angle formed at 29 between the adjacent parts of the head section 7 of the intermediate part and the normal section of the head of the rail.

It will be understood that the superficial profile of the upper part of the intermediate member may correspond to the normal profile of the head of the adjacent rail sections in order to avoid irregularities, and in order to ensure smooth running over the joint between the ends of the rail lengths. It will thus be understood that the passage of rolling stock over the rail joints is imperceptible and without shock or vibration, since the usual transverse joint is replaced by a joint having a broken configuration which approaches the longitudinal axis of the rail, and which does not permit of the independent flexure of the connected rail ends:

The intermediate member as hereinbefore described, is mounted by means of bolts 20, 21, 22, 23 in applying on the opposite side of the rail, an ordinary fish-plate 36 corre-

sponding to the plate 15 and adapted, as is the plate 15, to engage on the feet of the respective rails and the rail heads, and the rails are provided with corresponding holes or slots 30, 31, 32, 33 for the passage of these bolts.

I claim:

A joint for rails comprising in combination two adjacent lengths of rail whose respective ends are oppositely disposed in adjacent positions in line, the said lengths of rail having their heads recessed near their ends each respectively to form an inclined surface extending downwardly from the inner side of the rail head to the outer side thereof and to form a corresponding end face to extend transversely and outwardly from the inner side of the respective rail head to the outer side thereof, and an intermediate joining member having a head part whose profile corresponds to that of the head of the said rail lengths and of a form adapted to fit within the cavity constituted of the oppositely disposed recessed parts formed in the heads of the rail ends, the said head part of the joining member having inclined ends and an inclined under face and the said joining member being adapted to be secured to the adjacent ends of the rail lengths whereby the rail head part of the said joining member is maintained in position within the said cavity and in contact with the inclined faces thereof, substantially as hereinbefore described.

FRANCISCO FERNÁNDEZ ASENJO y PEREZ del RIO.
